UNITED STATES PATENT OFFICE

143,996

DESIGN FOR A FONT OF TYPE

Charles E. Riddiford, Washington, D. C., assignor to National Geographic Society, Washington,
D. C., a corporation of the District of Columbia

Application July 23, 1945, Serial No. 120,908

Term of patent 14 years

(Cl. D64—12)

To all whom it may concern:

Be it known that I, Charles E. Riddiford, a subject of the King of Great Britain, residing at Washington, District of Columbia, United States of America, have invented a new, original, and ornamental Design for a Font of Type, of which the following is a specification, reference being had to the accompanying drawing, forming part thereof.

The drawing illustrates face views of a font of type, showing my new design.

I claim:

The ornamental design for a font of type, as shown.

CHARLES E. RIDDIFORD.
